UNITED STATES PATENT OFFICE.

CHARLES MCLEOD, OF TORONTO, ONTARIO, CANADA.

CENTRIFUGAL SEPARATOR.

1,035,888.

Specification of Letters Patent. Patented Aug. 20, 1912.

Application filed September 6, 1910. Serial No. 580,506.

To all whom it may concern:

Be it known that I, CHARLES MCLEOD, of the city of Toronto, in the Province of Ontario, Canada, have invented certain new and useful Improvements in Centrifugal Separators, of which the following is a specification.

This invention relates particularly to the means of supporting and driving the bowl 10 of the separator. It is desirable to have the bowl supported so as to be vertically adjustable to enable the skim milk and cream outlets to be brought at any time into proper relationship to the discharge spouts. Vertical 15 adjustment is also needed when bowls of different size are employed at different times on the same frame.

This invention also relates to certain improvements in the means of supporting and 20 driving the bowl so that it may revolve freely about the axis in which its center of gravity lies, whether such axis coincides with the geometrical axis of the bowl spindle or not and to the arrangement and location 25 of the clutch whereby the bowl is left free to revolve after the driving shaft is stopped.

The nature and scope of the invention will 30 be best ascertained on reference to the following description taken in connection with the accompanying drawings in which—

Figure 1 is a vertical sectional elevation of my improved separator. Fig. 2 is a face view of the friction clutch. Fig. 3 is an 35 enlarged sectional elevation of the divided spindle and the divided tube in which its upper part is supported. Fig. 4 is a cross section on the line $x-y$ in Fig. 3.

In the drawings like letters of reference 40 indicate corresponding parts in the different figures.

A is the frame of the machine suitably shaped to support the different parts. This frame carries in suitable bearings the horizontal driving shaft B and also the horizontal intermediate shaft C. The driving shaft has secured thereon a gear wheel D meshing with the pinion E loose on the intermediate shaft but having a driving connection therewith through the medium of the friction clutch F, hereinafter more particularly described. The intermediate shaft drives the bowl spindle through the medium of the usual spiral gear G. The bowl spin-

dle is formed in parts, the lower part H 55 being driven as described from the intermediate shaft and having a step bearing I in the lower part of the frame. The upper end of the lower part H of the spindle runs in a steady bearing J carried by the frame 60 of the machine. This bearing is preferably a separate piece shaped as a frustum cone and dropped into a similarly shaped recess in the frame so that it is readily inserted in place or removed as desired.

The upper part K of the spindle is telescopically coupled with the lower part in order that the upper part of the spindle may be adjusted to vary the height of the bowl as hereinafter described, without affecting the lower part. I preferably form this telescopic coupling by boring out the upper end of the lower part of the spindle H, and inserting therein the lower end of the upper part of the spindle which is preferably reduced in diameter as shown. A pin L passes through the upper end of the lower part of the spindle and through a longitudinal slot a formed in the lower end of the upper part of the spindle. The upper 75 part of the spindle may thus be raised and lowered while maintaining a driving connection with the lower part. The upper part of the spindle passes through the two parts M and N of a supporting and adjusting tube and engages the upper part of the tube through the medium of a thrust bearing O, preferably of the ball bearing type shown particularly in Fig. 3.

The supporting tube is adjustable intermediate its ends preferably by having one part threaded to screw within the other part. In the drawings I show the lower part screwed into the upper, a lock nut M' being also provided to lock the parts as 90 adjusted. The lower part N of the tube preferably closely embraces the lower end of the upper part K of the spindle to form a steady bearing therefor. The steady bearing J of the lower part of the spindle 100 also serves to support the supporting tube, the lower part N of the tube resting on the bearing as shown. The engaging parts are preferably curved as shown particularly in Fig. 3 to permit of the supporting tube 105 swinging slightly on the bearing J as hereinafter described. The upper part M of the tube passes through an elastic bearing car-

ried in a sleeve or box R screwed into a suitable recess in the frame. This elastic bearing allows a slight vibration of the upper part K of the spindle, when the machine is running without the vibrations being imparted to the frame of the machine, the tube supporting the spindle rocking slightly as may be required on the steadyng bearing J while the elastic bearing tends 10 yieldingly to maintain the tube and the spindle carried thereby in their normal central position.

The elastic bearing is preferably arranged as follows: The upper part M of the tube 15 has a bearing in the annular disk Q loose in the sleeve R. Three or more springs V set in recesses in the disk Q bear against the inner periphery of the sleeve R and tend to center the said disk. A coil spring A' engages a disk or washer B' fitting within the sleeve or box R and loose on the tube M, and a collar W secured to the upper part M of the tube. This spring not only provides a 20 yielding pressure tending to hold the supporting tube down against the bearing J thus preventing the lifting and chattering of the tube on the support, but also by clamping the disk Q between the disk B' and the annular shoulder C' produces sufficient friction to dampen any rebound which 25 might cause the spindle and the tube to fly past the center by continued movement in the same direction in which they returned to the center.

30 The bowl is supported and given a driving connection with the upper part K of the bowl spindle by the following construction: The bottom of the bowl is concave, as shown, and in it is formed the socket S which fits the head of the conical connecting piece T fitted upon the upper end of the upper part K of the bowl spindle, as hereinafter described. The driving connection is formed between the bowl and the head by means of a trans- 45 verse feather b in the socket S which fits into a corresponding transverse slot formed in the top of the head of the connecting piece T.

The conical connecting piece T is connect- 50 ed to the bowl spindle in the following manner: The upper end of the upper part K of the spindle is made hemispherical in form and this in effect forms the ball d which is fitted into a similarly shaped socket formed 55 in the connecting piece. A slight play is allowed between the spindle and the recess in the connecting piece or head which permits of the connecting piece having a limited rocking movement in any direction on the 60 end of the spindle. The pin c projects from the connecting piece C into a slot e formed in the end of the spindle. This pin will form a driving connection between the spindle and the connecting piece without inter- 65 fering with the freedom of the latter to rock.

The connecting piece carrying the head will usually remain in position on the spindle while the bowl is readily lifted off whenever desired.

From the constructions I have described 70 it will be seen that the bowl is free to rock in order that it may rotate about an axis passing through its center of gravity. The spindle being supported in the tube which has an elastic supporting bearing on the 75 frame of the machine, is free to move in any direction to accommodate itself to the requirements of the rotating bowl without jarring the machine. The bowl also is 80 readily adjusted in height as required by screwing together or unscrewing the parts of the supporting tube.

I have hereinbefore referred to the clutch F which is located at the outer end of the intermediate shaft C. This is of an ordinary ball friction clutch type, the outer part 85 F being secured to the end of the shaft while the inner part U is fitted on the square extension f formed on the outer side of the pinion E. The friction members co-operat- 90 ing with the clutch members are the balls g operating in the wedge shaped spaces cut from the inner clutch member U, in the ordinary manner. This location and ar- 95 rangement of the friction clutch enables me to bring the pinion E close against the ad- jacent bearing of the intermediate shaft.

As the clutch is between the pinion E and the intermediate shaft C, when the driv- 100 ing shaft is stopped to allow the bowl to run down, the only other part moving beside the bowl and bowl spindle is the intermediate shaft worm wheel and outer member of the clutch, the gears D and E being idle. The particular arrangement described of the 105 shafts, gearing and clutch is thus of much importance as giving the greatest strength and steadiness when running and the least wear when the machine is running down. The clutch also takes up the driving of the 110 bowl very quickly when the power is applied to the driving shaft.

Owing to the difficulty of always keeping the recess in the connecting piece T of the proper size when tempering the piece, I prefer to employ the following means for preventing undue rocking of the bowl, in the event of the hole being a little too loose. A tight crimped spring D' fits in a shallow 115 annular groove within the piece and bears 120 against the spindle K, preferably through the medium of the sleeve E' secured to the spindle and forming part of the thrust bearing O (see Fig. 4). This spring effectively restrains undue lunging of the bowl. 125

What I claim as my invention is:—

1. In a centrifugal separator the combi- 130 nation of a bowl; a bowl spindle; a tube at the bowl end of the spindle in which the spindle has a thrust bearing and through the

- lower end of which the spindle projects; and means for vertically adjusting the tube to vary the height of the bowl.
2. In a centrifugal separator the combination of a bowl; a bowl spindle; a tube in which the spindle has a thrust bearing and through the lower end of which it projects; and a guiding bearing for the spindle at the lower end of the tube; and means for vertically adjusting the tube to vary the height of the bowl.
3. In a centrifugal separator the combination of a bowl; a bowl spindle; a tube at the bowl end of the spindle in which the spindle has a thrust bearing and through the lower end of which the spindle projects, said tube being formed of an upper and lower part; and means for vertically adjusting the upper part of the tube.
4. In a centrifugal separator the combination of a bowl; a bowl spindle; a tube in which the spindle has a thrust bearing; and means intermediate the ends of the tube for vertically adjusting the tube to vary the height of the bowl.
5. In a centrifugal separator the combination of a bowl; a bowl spindle; a tube in which the spindle has a thrust bearing, said tube being divided into upper and lower parts; and means intermediate the ends of the tube for vertically adjusting the upper part of the tube on the lower to vary the height of the bowl.
6. In a centrifugal separator the combination of a bowl; a bowl spindle; a tube; a thrust bearing between the spindle and the tube; an elastic bearing for the tube intermediate its ends; and means for vertically adjusting the tube to vary the height of the bowl.
7. In a centrifugal separator the combination of a bowl; a bowl spindle; a tube; a thrust bearing between the spindle and the tube; an elastic bearing for the tube intermediate its ends; and a sleeve carrying said elastic bearing and vertically adjustable on the frame of the machine.
8. In a centrifugal separator the combination of a tube guided at its lower end; an elastic bearing for said tube adjacent to its other end; a bowl spindle having a suitable bearing in said tube near its upper end and suitably guided at its lower end; a bowl; and a ball-and-socket connection between the upper end of the spindle and the bowl.
9. In a centrifugal separator the combination of a bowl; a bowl spindle; a tube in which the spindle has a thrust bearing, said tube being divided into upper and lower parts and the tube and spindle having a screw adjustment the one on the other; and a lock nut for holding the parts as adjusted.
10. In a centrifugal separator the combination of a bowl; a bowl spindle divided into upper and lower parts telescopically coupled; a tube in which the upper part of the spindle has a thrust bearing; bearings for the tube; and means for adjusting the tube to vary the height of the bowl.
11. In a centrifugal separator the combination of a bowl; a bowl spindle divided into upper and lower parts telescopically coupled; a tube in which the upper part of the spindle has a thrust bearing, said tube being divided into upper and lower parts; bearings for the tube and means for vertically adjusting the upper part of the tube on the lower.
12. In a centrifugal separator the combination of a bowl; a bowl spindle divided into upper and lower parts telescopically coupled; a tube divided into upper and lower parts; means for vertically adjusting the upper part of the tube on the lower; a thrust bearing between the upper part of the tube and the upper part of the spindle; a steady bearing between the same two parts; and a thrust bearing for the lower end of the lower part of the spindle; a steady bearing for the same near its upper end, the said steady bearing being also adapted to support the lower end of the divided tube.
13. In a centrifugal separator the combination of a bowl; a bowl spindle divided into upper and lower parts telescopically coupled; a tube divided into upper and lower parts; means for vertically adjusting the upper part of the tube on the lower; a thrust bearing between the upper part of the tube and the upper part of the spindle; a steady bearing between the same two parts; a thrust bearing for the lower end of the lower part of the spindle; a steady bearing for the same near its upper end, the said steady bearing being also adapted to support the lower end of the divided tube; and an elastic bearing steady the upper end of the divided tube.
14. In a centrifugal separator the combination of a bowl; a bowl spindle; a tube in which the spindle has a thrust bearing and means intermediate the ends of the tube for vertically adjusting the tube to vary the height of the bowl; steady means for the lower end of the tube; and a bearing for the lower end of the spindle independent of the tube.
15. In centrifugal apparatus the combination of a spindle; a disk encircling the spindle and displaceable therewith in a direction transverse of the axis of the bearing; springs engaging a stationary part and said disk tending to center the disk and spindle; an annular relatively stationary flange with which said disk contacts; and a spring engaging a relatively stationary part and said disk to produce friction between said disk and flange.
16. In centrifugal apparatus the combi-

nation of a spindle; a tube surrounding the spindle; a thrust bearing between the tube and spindle; a support for the lower end of the tube; an annular disk movable on but closely fitted to said tube; an annular relatively stationary flange with which said disk contacts; springs engaging a relatively stationary part and said disk tending to center the disk and spindle; and a spring engaging the disk and the tube tending to press the tube against its support and the disk against the flange.

17. In a centrifugal separator the combination of a bowl spindle suitably journaled having a ball formed at the upper end; a head having a socket to receive the ball and shaped to have a limited rocking movement

on the ball; and an annular crimped spring encircling the spindle and bearing against spindle and the head.

18. In a centrifugal separator the combination of a bowl spindle suitably journaled having a ball formed at the upper end; a head having a socket to receive the ball and shaped to have a limited rocking movement 25 on the ball; and a spring encircling the spindle and bearing against spindle and the head.

Toronto, this 30 day of August 1910.

CHARLES McLEOD.
